UNITED STATES PATENT OFFICE.

WALTER L. ECKHARDT, OF PHILADELPHIA, PENNSYLVANIA.

RADIO REPRODUCER.

Application filed June 11, 1926. Serial No. 115,159.

My invention relates to radio reproducers, and it has for its general object to provide a reproducer of novel construction of a character such that the tones reproduced thereby are clear, resonant, natural, free from "blast" and without rattle.

It is also an object of the invention to provide a construction of reproducer comprising a vibratory diaphragm and a resonance element of drum shape within which the said diaphragm is located.

The invention consists of a vibratory diaphragm of tapered shape supported only at its outer edges and mounted within and co-operating with a hollow tubular member of a length such that in cooperation with the vibratory diaphragm the requisite qualities of resonance and other characteristics of satisfactory sound reproduction are obtained.

20 To these and other ends the invention comprehends the construction and arrangement of parts as hereinafter described in detail, particularly pointed out in the claims and as illustrated in the drawings in which I have shown certain forms of mechanical embodiments thereof.

In the drawings:

Fig. 1 is a view in front elevation of a reproducer embodying the invention;

30 Fig. 2 is a view in transverse section taken in a central vertical plane at right angles to the plane of Fig. 1;

Fig. 3 is a vertical section of a fragmentary portion of the structure showing a modification of the means for securing the vibratory diaphragm within the drum or cylinder;

Fig. 4 is a view in front elevation of a reproducer showing a construction containing a modified embodiment of the invention;

40 and

Fig. 5 is a vertical transverse sectional view taken in a plane at right angles to the plane of Fig. 4.

Referring to the drawings,—it will be noted that the base comprises a portion 1 of relatively large size and a portion 2 of smaller size secured thereto and centrally thereof and that to the latter the cylindrical drum shaped member 3 is secured by means of screws 4 and 5. The member 3 in the construction shown is in the form of a hollow cylinder but may be of other shape in cross section. It consists of wood or of some other material having corresponding qualities as to amplification, resonance, etc. The member 3 may be described broadly as a section of a tube of large trans-

verse area. It is provided near its front end portion with an inner band 6 also of wood or similar material. Located interiorly of and near the front end of the tubular resonator 3 is a metal bar 10 which extends diametrically of the said resonator. The said bar is provided at its opposite ends with laterally extended projections 11 constituting feet which are seated against the inner side of the interior band 6 previously referred to. The said feet are provided with openings through one of which the screw 5, to which previous reference has been made, extends. The said screw extends not only through the lower foot 11 but also through the band 6 and the resonator 3 into the base of the device. The opening through the upper foot 11 is tapped and a screw 12 extends through openings in the resonator 3 and the band 6 and has screw threaded engagement with the said tapped opening. The screws 5 and 12 operate to secure the circular band 6 in place within the resonator 3 and also to secure the vertical metal supporting bar 10 in position.

In addition to the employment of screws 5 and 12 for securing the band 6 in place cement may be employed, if desired, between the outer surface of the said band and the inner opposing portion of the surface of the resonator 3 as an additional securing means.

The front edge of the band 6 may be located a short distance inwardly of the front edge of the tubular resonator 3, as is shown in the drawings, so as to provide a circular groove between the front edge of the band 6 and the adjacent front edge portion of the tubular resonator 3 for the reception of a circular frame 15 upon which is mounted suitable fabric 16 of silk or other similar material. The frame 15 with the silk mounted thereon constitutes a closure of the front end of the tubular resonator 3 so as to conceal the front portion of the mechanism within the resonator 3 from view.

A narrow band 18 is secured in the resonator 3 near the rear end thereof, as shown in Figs. 2, 3 and 5 of the drawings. This band forms with the inner edge portion a groove for the reception of a circular wire frame 20 upon which is mounted a fabric 21 of silk or other suitable material. The inner portion of the said fabric is connected to a ring frame portion 22 located concentrically of the tubular resonator 3. The portions 20, 21 and 22 constitute a closure for the rear end of the resonator 3.

In the several forms of construction a diaphragm 23 is provided of suitable thin sheet material, such as paper, parchment or the like. The diaphragm is tapered from a circular line 5 near its outer edge toward the rear of the reproducer where it is connected with the rear end of a rod 25, commonly called a "reed", the front end of which is connected to the vibratory element of a loud speaker or reproducer unit 26 mounted upon the metal bar 10 previously referred to. The usual line wires 27 are connected with the said unit. The outer portion of the vibratory diaphragm terminates in a rearwardly and laterally extending flange-like portion 28.

Referring to Figs. 1 to 3 of the drawings, it will be noted that the inner edge of the band 6 is tapered from its inner side outwardly as indicated at 30, and that the front side of the 20 outer edge portion of the flange 28 is seated against the surface of the said tapered portion.

In the construction as shown in Figs. 1 and 2 of the drawings the outer edge portion of 25 the flange 28 is secured to the inner edge portion of the band 6 by means of cement, as indicated at 31. It has been found that when the diaphragm is secured to the front edge of the band 6 in this manner the device operates with entire satisfaction and that the fastening is durable.

In Fig. 3 of the drawings I have shown a construction in which the outer edge portion of the flange 28 is held against the inner edge 35 of the band 6 by means of a retaining ring 33 of wood or other suitable material which is fastened in place by means of screws 34 which extend through the said ring and through the outer edge portion of the flange 28 into the band 6.

In Figs. 4 and 5 of the drawings I have shown a construction in which the vibratory diaphragm 23 is not supported directly upon the band 6 but on the contrary is supported 45 upon a frame 35 of wood which in turn is supported upon the metal bar 10. The frame 35 in the construction shown is circular but should be of a shape corresponding to the shape in cross section of the tubular resonator 50 for 3.

The frame 35 is provided upon its inner edge with an inwardly extending flange-like portion 36 the front side of which is tapered or beveled, as indicated at 37. The rearwardly inclined flange portion 28 of the diaphragm 23 is seated against the rear side of the said flange and is secured thereto by cement 38 or by any other suitable means. The diaphragm supporting frame 35 is secured to the metal bar 10 by means of headed bolts 39 the front ends of which are threaded and are in engagement with tapped openings provided in the bar 10 near its upper and lower ends.

65 The only difference between the bar 10

shown in Figs. 4 and 5 and the corresponding bar in the preceding figures of the drawings is that in said Figs. 4 and 5 the said bar 10 is provided with a central portion 10^a which is located out of alignment with the opposite end portions thereof. The opposite end portions extend inwardly and the said bar is mounted within the resonator 3 with its feet 11 extending toward the front instead of toward the rear as shown in Figs. 1 and 2 75 of the drawings.

It will be noted that the only essential difference between the constructions shown in Figs. 1 and 2 and 4 and 5 is that in the former the outer peripheral portion of the flange 28 80 is secured directly to the band 6 and consequently to the drum 3, whereas in the latter Figs. 4 and 5, the peripheral portion of the diaphragm is secured to a frame 35 which in turn is mounted upon the opposite end portions of the diametral bar 10.

It will be noted that in the construction shown in Figs. 4 and 5 the portion 1 of the base is of somewhat greater length than the corresponding portion in Figs. 1 and 2 of 90 the drawings. The purpose of lengthening the portion 1 of the base in Figs. 4 and 5 is to permit of the mounting of upright posts 40 upon the outer ends thereof the upper ends of which are provided with 95 heads 41 which are located upon the opposite sides of the tubular resonator 3 in diametral relation with respect to each other. These heads are provided with short projections 42 which contact with and are secured 100 to the said resonator for the purpose of constituting an additional support and steadyng means therefor. The posts or columns 40 consist of wood or other suitable material.

It may be noted that the rear end of the 105 reed 25 may be connected to the diaphragm 23 at its apex in any known manner.

It also may be noted that the front and rear closures of the tubular resonator 3 may be inserted and withdrawn at will, the said 110 closures being retained in place by friction of the peripheral surfaces thereof with the inner front and rear edge portions of the resonator 3.

While the tubular resonator 3 and the band 115 6 preferably consist of wood it is to be understood that these parts may be constructed of any other suitable non-metal material possessing the requisite qualities of resonance and other characteristics previously referred to.

By the employment of my invention I am enabled to construct radio reproducers which not only are very efficient for reproducing sounds having the characteristics and qualities already indicated, but which also are ornamental in high degree.

Having thus described my invention, what I claim and desire to secure by Letters Patent is:

1. A radio reproducer, comprising a resonator consisting of a section of non-metal material of tubular form and a band secured within one end of the said section, a bar extending diametrically of the said resonator and secured thereto at its opposite ends, a reproducer unit mounted on said bar, a vibratory diaphragm having operative connection at its outer edge to the said band, and a connection between the geometrical center of said diaphragm and the said reproducer unit.
2. A radio reproducer, comprising a resonator of wood consisting of a hollow cylindrical member and a band mounted within one end portion of the said member, a vibratory diaphragm having a circular portion tapered from a circular line near its outer edge to an apex, the portion of the said diaphragm beyond the said circular line constituting a flange, means for securing said flange to the inner edge of the said band, and means having connection with the said diaphragm at its apex for effecting vibrations thereof.
3. A radio reproducer, comprising in combination a wooden member of drum shape including a band upon the inner side of one end portion thereof, the inner edge of which is tapered from its inner side outwardly, a vibratory diaphragm the outer edge of which is secured to the inner tapered edge portion of the said band, a reproducer unit, and a connection between the said unit and the geometrical center of the said diaphragm, substantially as described.
4. A radio reproducer, comprising in combination a resonator of drum shape including a band upon the inner side of one end portion thereof, the inner edge of the said band being inclined rearwardly from its inner side, a vibratory diaphragm located within and extending transversely of the said resonator the outer edge of which is mounted upon the inner edge of the said band, means for securing the said diaphragm to the said band, a bar extending diametrically of the said resonator and secured at its opposite ends thereto, a reproducer unit mounted upon said bar, and a connection between the said unit and the geometrical center of the said diaphragm, substantially as described.

In testimony that I claim the foregoing as my invention, I have hereunto signed my name this 18th day of May, 1926.

WALTER L. ECKHARDT.
